DESIGN FOR A SHOE

Burton L. Wales, Abington, Mass., assignor to
The Stetson Shoe Company, Inc., Weymouth,
Mass., a corporation of Massachusetts

Application May 25, 1938, Serial No. 77,365

Term of patent 3½ years

To all whom it may concern:

Be it known that I, Burton L. Wales, a citizen of the United States of America and a resident of Abington, in the county of Plymouth, Commonwealth of Massachusetts, have invented a new, original, and ornamental Design for a Shoe, of which the following is a specification, reference being had to the accompanying drawing, forming part thereof.

In the drawing:

Fig. 1 is a plan view of a shoe, showing my new design, and

Fig. 2 is a side elevation.

I claim:

The ornamental design for a shoe, substantially as shown.

BURTON L. WALES.
